UNITED STATES PATENT OFFICE

HARRY B. WHITE, OF CANTON, OHIO, ASSIGNOR TO THE HOOVER COMPANY, OF NORTH CANTON, OHIO, A CORPORATION OF OHIO

SUCTION CLEANER

Application filed February 17, 1930. Serial No. 428,869.

The present invention relates to suction cleaners and more particularly to means for adjusting the height of the suction cleaner nozzle above the surface covering undergoing cleaning. More specifically the invention relates to new and novel means for adjusting the front wheels of a suction cleaner relative to the suction cleaner proper so that the cleaner is pivoted about the rear supporting wheels as an axis.

A suction cleaner must be adapted for use upon surface coverings of various thicknesses and degrees of stiffness and, in order that the machine may always function with maximum efficiency, it is necessary that the lips of the nozzle of the suction cleaner contact the surface covering undergoing cleaning, for without such contact the air enters the nozzle of the cleaner without passing over or through the surface covering and performs no useful function. When used upon a surface covering in which the pile or nap is relatively short, the front supporting wheels, which are positioned closely adjacent to the nozzle of the cleaner, will rest substantially upon the top of the surface covering without sinking into it and it is necessary to adjust the nozzle to a relatively low position in order that the nozzle lips may contact the covering. If, after the cleaner has been adjusted for efficient operation upon such a covering it is removed to a covering provided with long and soft pile into which the front supporting wheels will sink the nozzle lips will not only contact the top of the pile of the covering but will extend thereinto resulting in a condition in which the cleaner is hard to operate and in which it functions with reduced efficiency. In order to correct such an undesirable condition it is necessary to raise the nozzle relative to the surface covering so that its lips rest lightly thereon. By means of the present invention the necessary adjustment of the nozzle may be accomplished.

It is an object of the present invention, therefore, to provide a new and novel means for adjusting the height of the suction cleaner nozzle relative to the surface covering. A further object is the provision of means by which the nozzle height adjustment is accomplished with a minimum of effort and in which the adjustment once made is positive and permanent until intentionally altered. A still further object of the invention is the provision of novel height adjusting means in a suction cleaner by which the suction cleaner nozzle may be raised or lowered relative to the surface covering undergoing cleaning through the pivoting of the cleaner about the rear supporting wheels as an axis. Another object of the invention is the provision of an easily accessible nozzle height adjusting means. Other and more specific objects will appear upon reading the following specification and taking into consideration the drawings annexed thereto.

Referring now to the drawings:

Figure 1 discloses a partial side view of a suction cleaner embodying the present invention with certain parts broken away.

Figure 2 discloses a partial top view of a suction cleaner embodying the present invention with certain portions of the wheel pocket broken away in order that the invention may be clearly shown.

Figure 3 discloses a view upon the line 3—3 of Figure 2.

In the drawings and in Figure 1 in particular, the forward portion of a suction cleaner is shown and comprises a main casing 1 which forms the suction nozzle 2 and the fan chamber 3 within which is positioned a fan which is not shown. Two rearwardly and inwardly extending vertical walls 4 and 5 provide pockets at the two rear corners of the nozzle 2 for a purpose which is hereinafter described. A bottom plate 6 is carried by the walls 4 and 5 and cooperates with them to provide an air passage extending from the

mouth of the nozzle 2 in the direction of the eye of the fan chamber in the fan casing 3. A separately formed housing member 7, which is carried by the underside of casing 1, opens to the air passage formed by the walls 4, 5 and the bottom plate 6 and serves to further direct the air to the eye of the fan chamber. A motor casing 8 which is carried by the main casing 1 and contains a driving motor for the fan, and a handle bail 9, which is pivoted to the casing, are shown in the figures and comprise the parts found in the usual suction cleaner. Around the lower edges of the nozzle 2 is positioned a relatively soft resilient guard member 10 which is secured to the rearward wall of the nozzle by means of rivets 11, 11 and which serves to protect objects of furniture with which the cleaner may come into contact.

20 Positioned within each of the wheel pockets, formed by the walls 4 and 5 and the outer walls of the nozzle 2, are front supporting wheels, indicated by the reference characters 12, 12. Wheels 12, 12 are carried by short axles 13, 13 upon the extended ends of which are pivotally mounted the ends of links 14, 14 and 15, 15. A nut 16 is threaded upon one end of each shaft 13, the other end being upset, to maintain the assembly in operative relation.

25 The links 15, 15 are pivotally mounted at one of their ends to pins 17, 17 which are carried by the rearwardly extending outer walls of the nozzle 2 immediately in the rear of the juncture of that wall with the walls 4 or 5. The links 14, 14 extend forwardly and upwardly from the shafts 13, 13 and enclose at their opposite ends, the eccentrics 18, 18 which are fixedly carried by the transversely extending shaft 19 which is supported by bearings 20, 20 in the walls 4 and 5.

30 Carried at the ends of the shaft 19 and seated within recessed seats 21, 21 in the side walls of the nozzle are the circular plates 22 and 23 which prevent the longitudinal displacement of shaft 19. Plate 23 is formed as a manually rotatable knob and comprises a circular body-portion 24 which is provided on its inner side with spaced recesses 25, 25 and, on its outer side, with a protruding wall 26 of sufficient height that it may be readily grasped by the fingers of the operator. Positioned immediately below the operating knob-member 23 and secured by means of a rivet 27 to the wall of the nozzle is a spring 35 detent 28 the upper end of which coacts with one of the recesses 25 in the inner side of the cylindrical body portion 24 of the adjusting member 23 to maintain the position of that member in the absence of a positive turning torque.

The operation of the nozzle height adjusting means constructed in accordance with the present invention, is as follows:—The operator turns the knob 23 at the side of the

nozzle by means of the protruding wall 26 and the shaft 19, being fixedly connected to the knob, rotates with it as do the eccentrics 18, 18. As the eccentrics move about the axis of the shaft 19 the arms or links 14, 14 are either raised or lowered, depending upon the direction of rotation, and, depending whether arms 14, 14 are raised or lowered, the wheels 12, 12 which are attached to the ends of the arms are also raised or lowered about the pins 17, 17 as an axis, they being pivoted thereabout by means of the links 15, 15. As the knob 23 rotates the spring-detent 28 engages and disengages the successive recesses 25, 25 in the inner surface of plate 24, it being only necessary to exert a slight turning torque to overcome the locking tendency thereof. Upon the desired adjustment being secured the knob 23 is rotated so that detent 28 engages a recess in which relation it provides sufficient resistance to the rotation of shaft 19 to prevent the loss of the adjustment by means of any turning torque which might be transmitted to the cams 18, 18 from the wheels.

I claim:—

1. In a suction cleaner, a casing including a nozzle, nozzle height adjusting means comprising a horizontal rotatable shaft mounted on said casing, an eccentric carried by said shaft, a supporting wheel, an arm connected to said eccentric and to said wheel and rotatable about the axis of each, and a second arm pivoted to said casing and rotatably connected to said wheel, said parts cooperating for the purpose described.

2. In a suction cleaner a casing including a nozzle, a horizontal rotatable shaft mounted on said casing, an eccentric rigidly carried by said shaft, an arm pivoted to said casing, a supporting wheel carried by said arm, a second arm pivotally connected to said first-mentioned arm and to said eccentric and cooperating with said first mentioned arm to position said wheel, and means on said casing to rotate said shaft and move said wheel relative to said casing.

3. A suction cleaner comprising a nozzle casing, rearwardly and inwardly extending walls in said casing forming pockets at the corners thereof, supporting wheels in said pockets and means to synchronously adjust the position of said wheels relative to said casing comprising a rotatable shaft extending across said casing and through said pockets, eccentrics rigidly carried by said shaft in said pockets, means connected to said wheels and to said eccentrics, and means to rotate said shaft.

4. A suction cleaner comprising a nozzle casing, rearwardly and inwardly extending walls in said casing forming pockets at the corners thereof, supporting wheels in said pockets and means to synchronously adjust the position of said wheels relative to said

casing comprising a shaft rotatably mounted in said walls and extending across said casing, eccentrics rigidly carried by said shaft in said sockets, arms rotatably mounted on 5 said eccentrics and connected to said supporting wheels, and means positioned outside said casing to rotate said shaft.

Signed at North Canton, in the county of Stark, and State of Ohio, this 12th day of 10 February, A. D., 1930.
